PINWHEEL TOY OR SIMILAR ARTICLE

Arthur Halpern, New York, N.Y., assignor to M. I. Sales
Co., Inc., New York, N.Y.

Filed Mar. 1, 1971, Ser. No. 122,653

Term of patent 14 years

Int. Cl. D21—01

U.S. Cl. D34—15

FIG. 1 is a front elevational view of the pinwheel toy or similar article embodying my new design;

FIG. 2 is a side elevational view thereof;

FIG. 3 is a partial rear elevational view thereof; and
FIG. 4 is a cross-sectional view taken on line 4—4 of
FIG. 1.

I claim:

The ornamental design for a pinwheel toy or similar article, substantially as shown.
